DESIGN FOR A BRACELET OR THE LIKE

Louis C. Mark, Providence, R. I., assignor to Rice-
Weiner and Company, Providence, R. I.

Application June 30, 1941, Serial No. 101,807

Term of patent 3½ years

to all whom it may concern:

Be it known that I, Louis C. Mark, a citizen of the United States, residing in the city of Providence, county of Providence, State of Rhode Island, have invented a new, original, and ornamental Design for a Bracelet or the like, of which the following is a specification, reference being had to the accompanying drawing, forming part hereof.

Fig. 1 is a front elevational view of a bracelet or the like disclosing my new design and,

Fig. 2 is a side elevational view of the central portion of the bracelet or the like showing my new design, the chain being broken away.

I claim:

The ornamental design for a bracelet or the like, substantially as shown.

LOUIS C. MARK.
